[57] CLAIM

The ornamental design for a battery pack for use with portable power tools or the like, as shown and described.

DESCRIPTION

FIG. 1 is a front perspective view of the battery pack for use with portable power tools or the like showing a first embodiment of my new design;

FIG. 2 is a rear perspective view thereof;

FIG. 3 is a perspective view thereof showing the straps removed for clarity of disclosure only;

FIG. 4 is an enlarged front elevational view thereof;

FIG. 5 is an enlarged rear elevational view thereof;

FIG. 6 is an enlarged side elevational view thereof;

FIG. 7 is an enlarged opposite side elevational view thereof;

FIG. 8 is an enlarged top plan view thereof;

FIG. 9 is an enlarged bottom plan view thereof;

FIG. 10 is a front perspective view of the battery pack for use with portable power tools or the like showing a second embodiment of my new design;

FIG. 11 is a rear perspective view thereof;

FIG. 12 is a perspective view thereof showing the straps removed for clarity of disclosure only;

FIG. 13 is an enlarged rear elevational view thereof;

FIG. 14 is an enlarged front elevational view thereof;

FIG. 15 is an enlarged side elevational view thereof;

FIG. 16 is an enlarged opposite side elevational view thereof;

FIG. 17 is an enlarged top plan view thereof; and

FIG. 18 is an enlarged bottom plan view thereof.

FIG. 1.**FIG. 2.***FIG. 3.**FIG. 4.****FIG. 5.******FIG. 6.******FIG. 7.****FIG. 8.**FIG. 9.****FIG. 10.******FIG. 11****FIG. 12.**FIG. 13.**FIG. 14.**FIG. 15.**FIG. 16.**FIG. 17.**FIG. 18.*
